(74) *Attorney, Agent, or Firm* — Prakash Nama; Global IP Services, PLLC

(57) **CLAIM**

The ornamental design for a sling mount, as shown and described.

DESCRIPTION

FIG. 1 is a front elevation view of the first embodiment of a sling mount, showing my new design;
FIG. 2 is a rear elevational view thereof;
FIG. 3 is a left side view thereof;
FIG. 4 is a right side view thereof;
FIG. 5 is a top plan view thereof;
FIG. 6 is a bottom plan view thereof;
FIG. 7 is a perspective view thereof;
FIG. 8 is a second perspective view thereof;
FIG. 9 is a third perspective view thereof;
FIG. 10 is a fourth perspective view thereof;
FIG. 11 is a front elevation view of the second embodiment of a sling mount, showing my new design;
FIG. 12 is a rear elevational view thereof;
FIG. 13 is a left side view thereof;
FIG. 14 is a right side view thereof;
FIG. 15 is a top plan view thereof;
FIG. 16 is a bottom plan view thereof;
FIG. 17 is a perspective view thereof;
FIG. 18 is a second perspective view thereof;
FIG. 19 is a third perspective view thereof; and,
FIG. 20 is a fourth perspective view thereof.
The broken lines shown in sling mount form no part of the claimed design.
